WILLIAM T. McCABE, OF LOS ANGELES, CALIFORNIA

LIQUID DISPLACING APPARATUS

Application filed July 20, 1929. Serial No. 379,631.

This invention relates to a liquid displacing apparatus and particularly pertains to an automatic fluid-pressure operated liquid lifting mechanism of the type in which air or gas under pressure is employed to effect elevation and discharge of a liquid from a well by displacement of the liquid: the invention further pertaining to a valve structure arranged in the intake end of the apparatus, and to an automatic control mechanism at the discharge end thereof.

An object of the invention is to provide a pumping apparatus which is especially applicable for use in wells lined with tubular casings and to provide a construction and arrangement whereby the well casing is utilized as a conduit for air or gas under pressure employed in effecting discharge of liquid from the well and whereby only a single line of pipe is required in the apparatus other than the well casing, thus reducing cost of construction and installation as compared with fluid-pressure displacement pumps employing two or more pipe lines, and which arrangement is further advantageous in oil well operations in that it affords a back pressure in the well casing to prevent seepage of water through leaks in the casing.

Another object is to provide a well pump which in operation will allow the natural flow of liquid from the terrain into the well thereby minimizing the sanding up or clogging of the well: no vacuum being induced in the liquid bearing strata or sands to occasion such sanding up as frequently occurs in the use of suction pumps.

Another object is to provide a liquid lifting apparatus of the above character in which the use of packing is eliminated and in which the operating parts are so mounted and arranged as to minimize wear thereon thus obviating to a large degree any necessity of withdrawing the pump from the well to effect repairs and replacements thereof, thereby producing a pump system which, when installed, will endure for long periods of time without attention.

Another object is to provide a well pump of the type referred to which is automatic in operation and is capable of being adjust-

ed to adapt it to various capacities so as to obtain the maximum capacity.

A further object is to provide a well pump which may be readily assembled and installed, which is economical in construction and operation, which is durable and not liable to get out of order.

With the foregoing objects in view, together with such other objects and advantages as may subsequently appear, the invention resides in the parts and in the combination, construction and arrangement of parts hereinafter described and claimed and illustrated by way of example in the accompanying drawings, in which:

Fig. 1 is a view in vertical section, with parts broken away, of the portions of the pump structure applied to the upper and lower portions of the well casing;

Fig. 2 is a view in section and elevation of the pump showing it as applied;

Fig. 3 is a detail in section of the lower portion of the pump showing the sleeve valve in the alternate position to that shown in Fig. 1;

Fig. 4 is a view in section, with parts in elevation, of the float chamber located at the upper end of the well embodying the automatic control elements;

Fig. 5 is a detail in section and plan as seen on the line 5—5 of Fig. 4;

Fig. 6 is a detail in horizontal section as seen on the line 6—6 of Fig. 1;

Fig. 7 is a detail in horizontal section as seen on the line 7—7 of Fig. 1;

Fig. 8 is a detail in section on line 8—8 of Fig. 5, of the air or gas control valve.

Referring to the drawings more specifically, A indicates generally a well casing, B designates an automatic control element, C denotes the pump element and D designates the pump discharge conduit.

The casing A constitutes the usual well casing, the lower portion of which is extended into the liquid bearing sands or strata and is provided with a series of inlet openings 10 through which liquid flows from surrounding stratas into the lower portion of the casing.

In carrying out my invention, the upper end of the casing is fitted with a sealing cap 100

- 11 having an air or gas intake opening 12 through which air or gas is delivered into the well casing from a suitable source of air or gas supply directed through a pipe 13 connecting with the opening 12 and leading from the suitable source of supply of air or gas under pressure; the pipe 13 being equipped with a control valve 14 here shown in Figs. 5 and 8 as comprising a three-way valve of the rotary type.

The automatic control element B embodies a cylindrical wall 15 closed at its lower end with a bottom wall 16 and at its top end with a top wall 17. The walls 15, 16 and 17 enclose a float or receiving chamber 18 in which is disposed a float 19 adapted to move vertically on guide rods 20 and 21; sleeves 22 affixed to the float slidably engaging the guide rods.

- 20 The valve 14 includes a housing *a* formed with three ports *b*, *c* and *d*, and a valve member *e* formed with a T-passage *f*; the pipe 13 connecting with the port *b*, a pipe *g* leading from a suitable source of fluid pressure connecting with port *c*, and a pipe *h* leading from the float chamber 18 connecting with the port *d*.

A threaded stem 23 has screw engagement with the upper end of the float for longitudinal adjustment relative to the latter whereby the projecting length of the stem may be varied as occasion may require, and pivotally connecting with the upper end of the stem 23 is a link 24 leading to and pivotally connecting with the outer end of a crank 25 fixed on a rock shaft 26 mounted in a bearing 27 and extending through the upper portion of the cylinder 15 and connected to the valve member *e* in such manner that oscillation of the rock shaft 26 will effect turning of the valve member *e* in its housing *a* to dispose the valve in either of two positions according to the position of the float 19; the valve being disposed to direct fluid (air or gas) under pressure from pipe 9 to the well casing A through pipe 13 when the float is in its lowermost position, and being disposed to cut off the fluid pressure supply and to vent air or gas from the casing A and deliver the vented air or gas to the float chamber through the pipe *h* when the float reaches a predetermined elevated position.

- 55 Where the pump is applied to oil wells, a water drain pipe 29 is provided which communicates with the lower portion of the float chamber 18 through the bottom wall 16; the drain pipe being fitted with a normally closed manually controlled cut-off valve 30. An oil drain pipe 31 is provided which opens 60 to the float chamber at a point spaced above the bottom thereof and in spaced relation to the upper end of the water drain pipe, which oil drain pipe leads to a suitable point of discharge. A pipe 32 leads from the upper 65 end of the float chamber and leads to a gas

trap (not shown) from which the air or gas employed in operation of the pump may be drawn, and in which vapors may be condensed and collected.

The pump conduit D affords communication between the pump element C and the float chamber 18; the pump element C being disposed in the lower portion of the well casing and the pump conduit D leading therefrom through the well casing and passing 70 through a packing gland 33 on the cap 11 and opening to the float chamber 18 through a downwardly opening spout 34 leading through the upper portion of the cylinder 15, whereby liquid elevated by the pump element will be delivered into the float chamber. 75

The pump element C embodies a tubular upper end section 35 having a converging end portion 36 which is screwed into engagement 80 with the lower end of the pump conduit D, and having its lower end portion screwed into engagement with a tubular section 37 the lower end of which has screwed thereon a sleeve 38 formed with a pair of spaced flanges 85 39 and 40 forming an annular channel around the upper portion of the sleeve in which is disposed a sealing ring 41 preferably formed of lead or other soft metal. The ring 41 is adapted to frictionally engage the inner periphery of the well casing to afford a seal between the casing and the lower outer peripheral portion of the pump element. The lower end of the sleeve 38 is formed with an inturned marginal flange 42 which bears 90 against the lower end of the tubular section 37, the margin of which flange is bevelled and surrounds an opening which constitutes the intake of the pump element. The tubular section 37 is provided with a partition 43 which is spaced from the lower end of the section 37 and divides this section into upper and lower chambers 44 and 45 respectively, and the cylindrical side wall portion of section 37 above the partition 43 is provided 95 with a series of inlet openings 46 in the form of elongated longitudinally extending slots, arranged in circumferential rows with the upper row spaced below the upper end of the section 37 and through which openings fluid may pass from the well casing into the 100 interior of the tubular section 37. 105

Formed in the wall of the section 37, below the partition 43 and above the sealing ring 41 are openings 47 which serve as outlets through which liquid may pass from the perforated lower portion of the well casing into the imperforated portion thereof above the sealing ring 41; the latter being disposed at a point above the uppermost openings 10 of the 110 well casing. 115

Arranged in the section 35 is a nozzle 48 including a cylindrical wall 49 enclosing a chamber 50 in which is mounted a reciprocal piston 51; an annular flange 52 on the lower 120 125

end portion of the wall 49 being interposed between the inturned end flanges 53 and 54 on the contiguous ends of the sections 35 and 37 whereby the nozzle 48 is held in place. The 5 lower end portion of the nozzle with its engaging flanges constitutes a wall which separates the chamber 44 of the section 37 from the chamber 35' enclosed by the section 35. The wall 49 is formed with a series of openings 10 55 arranged adjacent the flange 53 which openings are adapted to be alternately opened and closed by the piston 51. The nozzle 48 is formed with a converging or conical upper end 48' which projects into the tapered or 15 converging end portion 36 of the section 35 and formed in the tapered end portion of the nozzle is an upwardly opening passage 56 leading from the end of the nozzle into the piston chamber 50.

20 The piston 51 is mounted on a piston rod 57 which extends downwardly through the chamber 44 and passes through the partition 43 being slidably in and guided by a collar 58 formed on the partition. Mounted on the 25 lower end of the piston rod 57 is a sleeve valve 59 the outer circumferential face of which slidably seats on the inner periphery of the lower end portion of the pump section 37, which sleeve valve is adapted on reciprocation 30 of the piston rod 57 to alternately open and close the openings 47.

The sleeve valve is connected to the piston rod by means of a hub 60 arranged interiorly 35 of the sleeve valve and connected to the latter by webs 61; the hub 60 encompassing a reduced end portion 62 on the piston rod 57 and abutting at its upper end against a shoulder 63 on the rod and being held thereagainst by a nut 64 screwed on the lower end of the 40 reduced section 62. The upper end of the hub 62 is tapered at 65 and is adapted to seat against the lower end of the collar 63 when the sleeve valve is in its uppermost position; the lower end of the collar 63 being bevelled 45 at 66 to provide a seat for the tapered upper end 65 of the hub 60 to seal the clearance space between the piston rod and the collar when the sleeve valve is in its uppermost position. This construction obviates the use of packing 50 between the piston rod and the wall 43. The piston 51 and the sleeve valve 59 are so spaced relatively to each other and are so related to the openings 47 and 55 that when the sleeve valve is in its lowermost position the openings 55 55 47 will be opened and the openings 55 will be closed and when the piston is in its uppermost position the openings 47 will be closed and the openings 55 will be opened.

In the operation of the invention liquid 60 flows naturally into the well casing through the openings 10 and passes upwardly through the interior of the sleeve valve when the latter is in its lowermost position and enters the well casing above the sealing ring 41 through 65 the openings 47 and thence flows into the

chamber 44 in the pump section 37 through the openings 46 thus affording a supply of liquid in the well casing above the sealing ring around the pump element and within the chamber 44. On directing air under 70 pressure into the well casing by opening of the valve 14 this pressure will initially be directed against the volume of liquid in the well casing A and will thereby displace a portion of the liquid and cause liquid pressure to be imposed on the lower end of the piston 51 thereby elevating the piston in the chamber 50 to uncover the openings 55 and also cause the sleeve valve to move upwardly and close 75 the openings 47. 80

On closing of the openings 47 communication between the source of liquid supply and the space in the well casing above the sealing ring 41 is closed so that the pressures developed by the incoming air under pressure 85 will not be directed against the liquid supply. The air under pressure will then act to effect displacement of the liquid above the sealing ring 41 and cause such liquid to flow from the chamber 44 through the openings 55 into the 90 chamber 35' in the pump section 35 upwardly around the nozzle 48. The chamber 35' in the section 35 above the openings 55 constitutes a compression chamber and by reason of having greater cross sectional area 95 than the conduit D, the liquid in flowing around the tapered nozzle and through the converging throat entering the lower end of the pump conduit will be directed into the latter with considerable velocity. On a quantity of the liquid being thus ejected from the chamber 44 the supply of fluid pressure to the well casing is cut off by operating the valve 14 to dispose the valve in position to 100 close the communication with the source of fluid pressure supply and to place the well casing in communication with the float chamber 18 through the pipe h, whereby the fluid pressure previously developed in the well casing will be reduced and a supply of the 105 fluid will be directed into the float chamber. 110

On reduction of pressure beneath the piston 51 the latter will tend to gravitate back to its normal lowermost position; this movement being augmented by liquid flowing into the chamber 50 above the piston through the passage 56. The openings 55 will then be closed by the piston to prevent back flow of the column of liquid in the pump conduit D and the openings 47 will be opened to permit 115 inflow of liquid from the well as before, whereupon the operation is repeated. 120

Timing of the fluid pressure impulses on the liquid in the well casing is governed and effected by movement of the float 19, which, in turn, is governed by the accumulation of liquid delivered to the float chamber. Discharge of the liquid from the float chamber through the pipe 31 is slower than the inflow of liquid to the float chamber; the out- 125

let through the pipe 31 being made sufficiently small to delay the flow of the liquid from the float chamber so that on a charge of the liquid being delivered to the latter the float 19 will be elevated sufficiently to effect operation of the valve 14 to cut off the supply of fluid pressure to the well casing. Upon cutting off the supply of liquid to the float chamber liquid accumulated above the upper end of the pipe 31 will drain from the latter, whereupon the float 19 will move downwardly and thereby effect reopening of the valve 14 to the source of fluid supply. The interval of time required for the liquid to drain from the float chamber and effect lowering of the float is such as to allow the refilling of the lower portion of the well casing by the natural seepage of the liquid through the liquid bearing sands or strata so that by the time the valve 14 reopens to direct another charge of fluid pressure into the well casing a volume of oil will have accumulated above the sealing ring 41 as before described in readiness to be ejected. The lapse of time between successive discharges of the liquid may be varied by raising or lowering the float 19 on its stem 23 so that the moment of the disposing of the float in the valve-opening position may be advanced or delayed.

By the use of this invention in oil wells, the vapors generated in the well may be recovered as they pass with the operating fluid from the well casing A into the float chamber 18 and are then delivered through the vent 32 of the latter to suitable condensers, thus avoiding waste of such vapors.

It is to be understood that the manner of carrying the invention into effect is herein specifically set forth to enable those skilled in the art to make and use the same and is to be considered as illustrative and not in a limiting sense; and that various changes may be made in the parts and in their construction and arrangement within the meaning of the terms and scope of the appended claims without departing from the spirit of the invention.

I claim:

1. In a liquid displacing apparatus, the combination with a well casing having liquid inlet openings in its lower end portion, a single discharge conduit disposed in said casing, a pump element on the lower end of said conduit, means carried on said pump element for affording a seal between said element and the well casing above the inlet openings in the latter, fluid pressure operated means embodied in said pump element for alternately opening and closing communication between the portion of said well casing below said seal and the portion above said seal, means for intermittently confining an operating fluid under pressure in said well casing to effect operation of said last-named means,

and means embodied in said pump element whereby the confined fluid under pressure will operate to effect displacement of liquid in the portion of the well casing above said seal and deliver it to discharge through said conduit. 70

2. In a fluid pressure operated liquid displacement pump, a pump element for positioning in a well casing, said pump element including upper and lower tubular sections, a partition separating the lower section into two superposed chambers, said lower section being formed with openings above and below said partition, a sealing ring surrounding the lower sections below the openings therein, 80 said lower section being open at its lower end, a reciprocal sleeve valve in said lower section beneath said partition operable to cover and uncover the openings below said partition, a communication between the tubular sections, 85 and a piston in said communication connected to said sleeve valve; said piston being operable by fluid pressure applied therebeneath to open said communication and to move said sleeve valve to its opening covering position. 90

3. In a fluid pressure operated liquid displacement pump, a pump element for positioning in a well casing, said pump element including upper and lower tubular sections, a partition separating the lower section into two superposed chambers, said lower section being formed with openings above and below said partition, a sealing ring surrounding the lower sections below the openings therein, 95 said lower section being open at its lower end, 100 a reciprocal sleeve valve in said lower section beneath said partition operable to cover and uncover the openings below said partition, a communication between the tubular sections, and a piston in said communication connected to said sleeve valve; said piston being operable by fluid pressure applied therebeneath to open said communication and to move said sleeve valve to its opening covering position and means whereby a column of 110 liquid in said upper section will operate to depress said piston to close said communication when the fluid pressure therebeneath is sufficiently reduced. 105

4. In a fluid pressure operated liquid displacement pump, a pump element for positioning in a well casing, said pump element including upper and lower tubular sections, a partition separating the lower section into two superposed chambers, said lower section being formed with openings above and below said partition, a sealing ring surrounding the lower sections below the openings therein, 115 said lower section being open at its lower end, a reciprocal sleeve valve in said lower section beneath said partition operable to cover and uncover the openings below said partition, a communication between the tubular sections, 120 and a piston in said communication connected to said sleeve valve; said piston being oper- 125

able by fluid pressure applied therebeneath to open said communication and to move said sleeve valve to its opening covering position, said upper section having a reduced tapered 5 upper end, a discharge conduit connected to the reduced end of said upper section, a tapered nozzle projecting into said tapered upper section formed with a chamber in which said piston is reciprocably mounted 10 and formed with an upwardly opening passage leading from said chamber whereby liquid may flow from said upper section into said chamber and act to depress said piston when fluid pressure beneath the piston is sufficiently reduced.

15 5. In a fluid pressure operated liquid displacement pump, a pump element for positioning in a well casing, said pump element including upper and lower tubular sections, 20 a partition separating the lower section into two superposed chambers, said lower section being formed with openings above and below said partition, a sealing ring surrounding the lower sections below the openings therein, 25 said lower section being open at its lower end, a reciprocal sleeve valve in said lower section beneath said partition operable to cover and uncover the openings below said partition, a communication between the tubular 30 sections, and a piston in said communication, a rod connecting said piston to said sleeve valve passing through said partition, and means on said rod operable to close a clearance space between the rod and partition when 35 said sleeve valve is in its opening covering position.
